DESIGN FOR A CONTROL HANDLE UNIT

William J. Turnbull, Garden City, N. Y., assignor
to The Glenn L. Martin Company, Baltimore,
Md.

Application September 2, 1942, Serial No. 108,103

Term of patent 14 years

(Cl. D10—8)

To all whom it may concern:

Be it known that I, William J. Turnbull, a citizen of the United States and a resident of Garden City, Long Island, in the county of Nassau and State of New York, have invented a new, original, and ornamental Design for a Control Handle Unit, of which the following is a specification, reference being had to the accompanying drawings, forming part thereof.

Figure 1 is a perspective view of a control han-

dle unit showing my new design, the fragmentary showing in dotted lines being for illustrative purposes;

Figure 2 is a side elevation of one of the control handles, shown in Figure 1; and

Figure 3 is a front elevational view thereof.

I claim:

The ornamental design for a control handle unit, substantially as shown and described.

WM. J. TURNBULL.
